SMOKING PIPE FILLER

Harold A. Thayer and John L. Surbeck,
Chicago, Ill.

Application October 12, 1946, Serial No. 702,920

4 Claims. (Cl. 226—126)

1

This invention relates to smoking articles and has more particular reference to filling smoking pipes with tobacco.

Our invention has particular reference to the filling of a smoking pipe under conditions which ordinarily present some difficulty as, for example, while the smoker is seated in or driving an automobile, or under any circumstance where a mechanical aid would facilitate the filling of a pipe. A principal object of our invention is, therefore, to provide new and improved means for filling a pipe with tobacco, and particularly such means as may be applied to the dashboard of an automobile, or to any wall support or the like, or to a smoking stand or cabinet.

Another object of our invention is to provide an improved pipe filler characterized by means for holding a pipe with its bowl portion in a position for filling and means actuated by the operator for causing the tobacco particles to be moved in small quantities from a hopper into the pipe bowl which is supported in such filling position and whereby such small quantities may be successively packed into the pipe bowl so as to give a proper filling.

Another object of our invention is to provide a pipe filler of the character described in which the several means are arranged in coacting relation in a unit of assembly adapted to be supported in the face of a wall structure or cabinet and including a tobacco receiving hopper mounted for refilling from the front of the wall as distinguished from a top filling. Such an assembly is particularly desirable as applied to the dashboard of an automobile.

Another object is to provide improved means for moving and guiding the tobacco from a hopper through a feed passage and into the bowl of a pipe without the tobacco bridging or clogging but rather in a manner to permit the free passage and feeding of small quantities of tobacco by a feeding means which also serves to press or tamp the tobacco into the pipe bowl and thus enable filling of the pipe to a desired degree of compactness suitable to the user.

Another object is to provide a pipe filler characterized by a passage located between a hopper and the pipe bowl having side walls of yielding or resilient material such as soft rubber which in coaction with a tobacco pushing means serves to

2

prevent a too rapid flow of the tobacco and yet normally provides a restriction which automatically cuts off the flow of tobacco to the bowl.

Another object of our invention is to provide an improved pipe filler which is automatic in respect to certain of its functions.

Another object is to provide a pipe filler of the character described which may be manufactured at a comparatively low cost.

10 Other objects and attendant advantages will be appreciated by those skilled in this art as the invention becomes better understood by reference to the following description when considered in connection with the accompanying drawings, in which:

Figure 1 is a view in perspective showing a pipe filler embodying our invention applied to a vertical wall structure such as the dashboard of an automobile;

20 Figure 2 is a vertical section through a pipe filler embodying our invention;

Figures 3, 4, and 5 are horizontal sections taken substantially on the section lines 3—3, 4—4, and 5—5, respectively, of Figure 2;

25 Figure 6 is a vertical section through the tobacco feeding portion of our pipe filler showing a modified form;

Figures 7, 8, and 9 are horizontal sections taken on the section lines 7—7, 8—8, and 9—9, respectively, of Figure 6; and

30 Figure 10 is a top view of the shutter-like closure members used in the latter form, removed from the device.

Referring to the embodiment shown in Figures 35 1 to 5, inclusive, we have shown a form characterized by a casing or housing designated generally by 11 enclosing an upper compartment 12 and a lower compartment 13. In this embodiment the upper compartment encloses a tobacco 40 containing hopper designated generally by 14 which is pivotally supported at 15 so that it may be tilted forwardly on such pivot to an open position indicated in dotted lines 16 in Figure 1 for the purpose of filling the hopper, and tilted backwardly to the operative position shown in full lines in Figure 2, in which latter position a pipe is to be filled with tobacco from the hopper. The hopper 14 may be of suitable construction and it is here shown as comprising side walls 17 and 18, front and rear walls 19 and 21, respec-

tively, and a bottom wall structure designated generally by 22, having a tobacco feed passage 23. The top of the hopper is open as shown in Figure 2 so that when the hopper unit is tilted forwardly it may be filled from the front with tobacco. The lower compartment is provided at its front with one or more normally closed doors 24 arranged to be opened by insertion of the bowl end of a pipe to a filling position and to close upon withdrawing the pipe through the front. In this case each door is hinged to turn about a pin 25 and a suitable spring 26 is arranged to yieldingly urge each door to the closed position shown in full lines in Figure 5. Each door is provided with a guide member 28, best shown in Figures 2 and 5, arranged in diverging relation one with respect to the other so that upon insertion of a pipe bowl as by pushing it inwardly against the doors 24, the bowl will ride against the extensions 26 and swing the doors to a full open position when the bowl reaches the filling position shown in dotted lines 27 in Figures 2 and 5. It follows that when the pipe is withdrawn the bowl will allow the extensions 26 to swing outwardly to the closed position. Means are provided for yieldingly guiding the pipe bowl to the filling position comprising a bottom spring guide 28 and side spring guides 29 which serve to engage the pipe bowl and center and locate it vertically with respect to the filling opening 23. Thus by merely inserting the bowl end of a pipe as by an inward pushing movement, the bowl is automatically centered and located in a filling position without need for care and precision on the part of the operator in so placing the pipe.

Our invention provides improved means for filling a pipe bowl from the hopper when the bowl is located in the filling position. To this end we have provided in the described embodiment, one or more layers of resilient material defining the wall of the passage 23. In this embodiment we have provided an upper layer 31 and a lower layer 32 each of yieldable or resilient material such, for example, as a porous or sponge-like soft rubber. In this case the lower wall structure 22 is composed of multi-layers which are perforated to provide an opening 33 of considerably larger diameter than the opening 23 and located eccentric with respect thereto as shown in Figures 2 and 4. The lower layer 32 of soft rubber is compressed between upper and lower layers 34 and 35 of the wall structure 22 so that the portion of the rubber disposed within the opening 33 is in a normal condition and free to be expanded or distorted from a normal position. The filling passage 23 above described is formed in the upper and lower layers 31 and 32 in the location shown. Each of these layers 31 and 32 is radially slotted as at 36 to provide a greater degree of passage opening and to allow a certain amount of distortion of those portions of the soft rubber layers contiguous to the passage 23. The upper layer 31 is preferably beveled at 37 for a limited area to provide for clearance of the pushing and tamping head 36. This head is normally supported within the passage 23 so as to provide a closure therefor. Means is provided for actuating the head 36 in a manner to withdraw it from its closure position to a position within the hopper and to advance it in a downward direction in a feeding stroke. By means of this back and forth movement of the head 36 the tobacco is worked partly by gravity and partly by pressure of the head into and through the passage 23 and into the pipe bowl.

By reason of the resilient character of the passage opening the tobacco displaces the passage walls when being forced down into the bowl and these walls serve to strip off the tobacco or retain it in the bowl against being drawn back into the hopper. By successive operations of this kind the tobacco is delivered into the bowl in successive quantities and is tamped in the bowl by the action of the head until the bowl is filled. 5 As a simple means for actuating the head 36 we have provided a rod 37 attached to the head and extending through a suitable bearing support 38 and another at 39 in the front wall of the hopper, and to the front end of the rod we attach a suitable knob 41 for manual operation. Thus the operator by grasping the knob 41 may work the plunger head 36 back and forth coplanar with the rod 37 and may also impart a certain amount of sidewise tilting movement to the head for the 10 purpose of loosening the tobacco in the hopper or for working the tobacco into and through the filling passage.

The soft rubber walls of the passage 23 combined with the action of the plunger head serve 15 to permit feeding of limited amounts of tobacco from the hopper into the pipe bowl, the rubber passage walls opening to a wide area under pressure of the plunger head when forcing a charge of tobacco in a feed stroke, and said walls contracting to their normal small area after passage of the tobacco and serving as an effective closure against further flow of tobacco from the hopper. It will be observed that the pipe may be held by one hand in the filling position while 20 the other hand operates the knob 41 to perform the filling operation, or the filling operation may be performed entirely by the one hand on the knob 41 because the pipe will be supported in position by the spring guides 26, 28, and 29. 25 This eliminates the use of a tobacco pouch or similar container and provides a means for quickly filling the pipe with the use of only one hand. This filling may conveniently be done 30 while driving an automobile, assuming the device is mounted in the dashboard or in the wall structure of the car. In view of the foregoing description, application of the device to a smoking stand, or a cabinet, or desk, or other support, 35 will be obvious.

30 In Figures 6 to 10 we have shown a modified form of the invention, in which the bottom of the hopper is equipped with a pair of shutter-like closure members designated generally by 42 and 43. In this embodiment, as is here shown, the hopper has a filling opening 23 and a soft rubber bottom wall 31, a plunger head 36, and a plunger operating rod 37, similar to these parts described above. The closure members 42 and 43 are alike in construction and normally occupy the closed position shown in the drawings. 35 Such closure members are pivoted respectively at 44 and 45 to the bottom of the hopper structure and each comprises a sheet metal body having a flat portion 47 slidable horizontally 40 between parts 43 and 49 of the hopper bottom structure. In these movements the members 42 and 43 swing about their pivots to open and closed positions. Each such member has suitably attached to its top surface a soft rubber 45 piece 51 which with the opposite member provides an opening 52 in alignment with the opening 23. The bottom part 49 is cut away to provide a circular opening 53 corresponding substantially in size and location with the opening 33 above described. In this case each body por-

tion 47 is provided with tabs 54 pressed over the top of the soft rubber member to hold it in position. Each soft rubber member is slotted as at 55 similar to the slitting in the soft rubber members above described. Each such member 42 and 43 is provided with a down-turned portion 56 which extends through an arcuate opening 57 in the bottom member 49, in which opening is disposed a coiled compression spring 58 which acts against the member 56 and yieldingly holds its shutter member in the closed position. Each such member 42 and 43 has fixed to its portion 56 an inclined guide 59 arranged to be engaged by a pipe bowl when the latter is inserted into the device and a guide 61 at its opposite end adapted to be engaged by the pipe bowl when the latter is moved into the filling position, to thereby hold its closure member in the open position. These guide members 59-61 form a continuous guide surface against which the pipe bowl moves from the inner to outer positions.

It will be apparent that these shutter-like members normally close the passage 23 and that they will be moved to an open position upon insertion of the pipe bowl to the filling position above described. In this position the portions of the soft rubber pieces 51 contiguous to the opening 52 will function as further guides to passage of the tobacco particles into the pipe bowl and they will have a yielding or expanding function similar to the soft rubber walls described in connection with the first embodiment.

In further embodiments the pipe supporting and the pipe filling means may be arranged in cooperative relation in casing structures other than the structure herein disclosed, in which arrangements the essential filling functions would be performed. In the casing embodiment here described we have included a container 61 in the form of an open top drawer located in the bottom of the casing adapted for catching any tobacco particles which may drop to the bottom. This drawer may be pulled forwardly as shown in dotted lines in Figure 2 for removal of this surplus tobacco.

It is believed that the foregoing conveys a clear understanding of our invention and it should be apparent that changes may be made in the construction and arrangement of parts within the spirit and scope of the invention as set forth in the following claims.

We claim:

1. A pipe filler comprising, in combination, a tobacco container having a bottom discharge opening, means for supporting a pipe beneath and in filling relation with the discharge opening, said pipe container being in the form of an open top hopper having a front wall, housing means normally closing the top of said hopper, means supporting said hopper so that it is tilttable forwardly to a position in which its open top is outside said housing means to permit filling the hopper through said open top, the hopper being tilttable backwardly to a position in which its open top is closed by said housing means, means actuated by the pipe in the movement thereof to said filling position to permit flow of tobacco through said opening into the pipe, and operating means manually operable from the front of said hopper for pushing tobacco from said container through the discharge opening for deposit into the pipe bowl.

2. In combination a pipe container having a bottom discharge opening, means for supporting a pipe bowl in a filling position beneath said opening, resilient means in the bottom of the con-

tainer arranged around the discharge opening so as to normally support tobacco within the container and prevent it from feeding through said opening, a plunger element disposed in the container above said opening and having manually operable means extending to the exterior of the container and operable thereby in feed and return movements toward and from said discharge opening, shutter-like means intermediate said resilient means and said pipe bowl normally providing a further closure to passage of tobacco from said discharge opening into the pipe bowl and being movable to an open position, said plunger being operated in said feed movement to press tobacco through and beyond said resilient means and said resilient means being displaceable to allow passage of said tobacco through said opening and into the pipe bowl.

3. A smoking pipe filler comprising, in combination, a casing having an upper and a lower compartment, a tobacco hopper within the upper compartment pivotally mounted to tilt forwardly and backwardly therein and having a front wall normally closing the front of the upper compartment when the hopper is in the backward tilted position, the hopper being tilttable forwardly to an open position in which it may be filled at its top through the front of the casing, the lower compartment being provided at its front with a closure normally closed and adapted to be opened for the insertion of the bowl end of a pipe, means for guiding said inserted pipe bowl to a filling position within the lower compartment, a discharge opening in the bottom of the tilttable tobacco hopper arranged to be in filling relation to the pipe bowl in said filling position thereof when said hopper is tilted to said backward position, operating means manually operable from the front of said hopper for pushing tobacco from said container through the discharge opening for deposit into the pipe bowl, and displaceable soft rubber means associated with the pipe discharge opening for normally retarding passage of tobacco from the container into the pipe bowl, said operating means including plunger means for pressing tobacco from the container through said discharge opening and through said displaceable soft rubber means for the discharge of said tobacco into the pipe bowl.

4. A smoking pipe filler comprising, in combination, a casing having an upper and a lower compartment, a tobacco hopper within the upper compartment pivotally mounted to tilt forwardly and backwardly therein and having a front wall normally closing the front of the upper compartment when the hopper is in the backward tilted position, the hopper being tilttable forwardly to an open position in which it may be filled at its top through the front of the casing, the lower compartment being provided at its front with a closure normally closed and adapted to be opened for the insertion of the bowl end of a pipe, means for guiding said inserted pipe bowl to a filling position within the lower compartment, a discharge opening in the bottom of the tilttable tobacco hopper arranged to be in filling relation to the pipe bowl in said filling position thereof when said hopper is tilted to said backward position, operating means manually operable from the front of said hopper for pushing tobacco from said container through the discharge opening for deposit into the pipe bowl, and displaceable soft rubber means associated with the pipe discharge opening for normally retarding passage of tobacco from the container into the pipe bowl, said

manually operable tobacco discharging means comprising a plunger element in coacting relation with said discharge opening, said operating means including means for operating said plunger element in a back and forth stroke wherein the plunger element serves to push tobacco through said displaceable soft rubber means for discharge into said pipe bowl.
